ROAD SIGN

Application filed July 27, 1925. Serial No. 46,386.

This invention relates to warning road signs, especially as provided for the highways in warning motorists of danger, either from curves in the road or other reasons.

5 The objects of the invention are to provide an improved sign for the purpose outlined particularly adapted for night warnings, which will give a pre-warning of danger followed by a setting forth of the specific danger, 10 also such a sign which when used at the curve of a road will both warn a motorist of the curve ahead and at the same time warn another motorist coming from around the curve of the approach of the first motorist, or 15 each motorist of each other's approach though hidden from one another's view by the curve.

We achieve the objects outlined by the special sign construction shown in the accompanying drawings and in which:—

20 Figure 1 is a front elevation of a sign post embracing our invention warning of a curve in the road;

Figure 2 is an enlarged fragment of the warning figure of Figure 1 as seen from the front side thereof, showing in elevation the reflecting fins and openings on the figure;

Figure 3 is an enlarged fragment of Figure 2 showing one of the fins and openings;

Figure 4 is a cross section of Figure 3 as 30 seen from the line 4—4 thereof; and

Figure 5 is a diagram of a road with a curve and two automobiles approaching the curve from opposite sides and showing an enlarged section of our sign at various points 35 in the road to illustrate the practical application of the invention.

In the drawings, the body of the sign 1 is a plane surface stating the nature of the danger, as by the word "Curve" painted 40 thereon, and which may be on one or both sides of the sign, and across the face of the sign is a pre-warning danger signal such as the arrow 2 but which of course may be given any suitable shape depending on the warning 45 to be conveyed.

The signal 2 is especially formed to function with the impinging rays of an automobile headlight so as to produce a variety of useful results—and in the enlarged details, 50 Figures 2, 3 and 4, this special formation of

the signal figure is shown to consist of a series of openings 3 through the sign and each opening having a vertically arranged fin 4 extending angularly outward from one edge of the opening.

This fin may extend from either side of the opening or from both sides as at 4' and the angle of extension may vary, all depending on the nature of the result desired.

The fins may be formed integrally with the sign body, especially if the latter is of sheet metal, by punching out from one side in the manner indicated in Figure 4, or the fins may be separately attached, and they may be of any desired color, reflective surface or what not, depending on the effect desired.

However, for the purpose of a danger road sign which will be particularly effective at night the fins are made highly reflective and also preferably slightly corrugated as indicated in Figure 4 at "A" so that the rays of a headlight striking the fins will be somewhat dispersed in leaving the surfaces of the fins.

The practical applications of the invention are many, but in Figure 5 enough are shown 75 for the purpose of this application.

The figure shows a highway B having a curve at C and with two automobiles D and E, each on their right hand side of the road, headed toward the curve from opposite directions, and at several places, such as F, G and H, is indicated in relatively enlarged section a fragment of our sign having one opening and fin element angularly arranged with respect to one or both automobiles to produce 85 various effects.

If the sign be arranged as at F the fins 4 and 4' will receive the light rays R from automobile D, thus illuminating the warning figure and also reflecting it through the openings in direction of automobile E. Or, conversely, the ray R' of the latter vehicle would illuminate the warning figure and transmit it to vehicle D.

The flat part 1 of the sign could also be 95 painted or impressed with suitable legends.

If the sign were placed at G as indicated and the outside surface of the fins made reflective, then the rays R of vehicle D would make the warning figure stand out in bright 100

relief against an invisible ground 1, and as the vehicle gradually neared the sign the ground would become visible so that the reason for the warning word "Curve", or whatever it may be, as painted thereon would also be brought to the attention of the motorist—thus he is pre-warned by a danger signal to slow down, and then told the nature of the danger.

10 Of course in arranging the fins to form a warning figure in the form of a curved arrow as shown at 2 in Figure 1, both warnings are to a certain extent combined, though there are other sources of road danger such as a
15 washout, road repairs, etc., where the pre-warning signal would take some standard form to be adopted and the detailed warning message suited to the precise conditions.

The sign could also be placed as at H so as
20 to virtually combine the two warnings, or in any other way to meet any special condition necessary or desired in order to attract the attention.

We claim:

25 1. A road sign of the character described comprising a plate adapted to be supported at a road intersection to reflect the rays thrown thereon by the headlight of an approaching vehicle for drawing the attention
30 of its driver, the said plate having an unobstructed rear face and having small sections thereof bent out of its plane to deflect rays striking the latter sections along the rear face upon the intersecting road for warning a
35 driver approaching thereon.

2. A road sign of the character described comprising a plate adapted to be supported at a road intersection to reflect the rays thrown thereon by the headlight of an approaching vehicle for drawing the attention of its driver, the said plate having an unobstructed rear face and having small sections thereof bent out of its plane to deflect rays striking the latter sections along the rear face
40 upon the intersecting road for warning a driver approaching thereon and the said sections being arranged to outline an informing signal to the first driver.
